US00D542090S

(12) **United States Design Patent** (10) **Patent No.:** **US D542,090 S**
(45) **Date of Patent:** **** May 8, 2007**

(54) **HANDLE FOR ELECTRONIC OVEN**

(75) Inventor: **Kang-Doo Kim**, Seoul (KR)

(73) Assignee: **Samsung Electronics Co., Ltd.**,
Kyunggi-do (KR)

(**) Term: **14 Years**

(21) Appl. No.: **29/266,197**

(22) Filed: **Sep. 15, 2006**

(51) **LOC (8) Cl.** **07-02**

(52) **U.S. Cl.** **D7/402**

(57) **CLAIM**

The ornamental design for handle for electronic oven, as shown and described.

DESCRIPTION

FIG. 1 is a top front perspective view of a handle for electronic oven showing our new design;
FIG. 2 is a front elevational view thereof;
FIG. 3 is a rear elevational view thereof;
FIG. 4 is a left side elevational view, the right side being symmetrical thereof; and,
FIG. 5 is a top plan view, the bottom plan being symmetrical thereof.
